UNITED STATES PATENT OFFICE.

PAUL ELSÄSSER, OF UNTERKULM, SWITZERLAND.

THERMOSTATIC CIRCUIT CLOSER.

Application filed October 26, 1921. Serial No. 510,581.

To all whom it may concern:

Be it known that I, PAUL ELSÄSSER, a citizen of the Swiss Confederation, residing at Unterkulm, Switzerland, have invented 5 certain new and useful Improvements in Thermostatic Circuit Closers, of which the following is a specification.

This invention relates to a fire-alarm apparatus which can be used with rooms of 10 any kind and which sounds a rapid and effective alarm when fire breaks out.

According to the invention the fire alarm apparatus, which is inserted in an electric circuit which comprises further a source of 15 current and an acoustic signal, comprises at least one contact drum revolvably arranged upon a plate and having insulating surfaces, and contact springs sliding upon said drum. The contact drum is controlled 20 by a spring and it has an arm held in position by a device of easily inflammable material. The arrangement is such that when fire breaks out the holding device is ignited and burned, whereby the arm of the contact drum is released and the drum is 25 revolved into the contact position by the action of the spring.

In order that the invention may be clearly understood, I shall proceed to describe the same with reference to the form 30 of construction shown on the accompanying drawing, wherein:—

Fig. 1 is a front elevation of the apparatus with the diagram of the electric connections.

Fig. 2 is a plan view of the apparatus with protecting case removed.

Fig. 3 is a section on line A—A of Fig. 1. 35 *a* is a metal plate which has two flaps *b* by means of which the plate is fixed upon the wall of the room. Upon the plate *a* two supports *c* are arranged in which the axles *d* of two brass drums *e* are journaled. Each drum *e* has two insulating 40 surfaces *f* upon its circumference which are formed preferably by layers of fibrous material sunk into the surface of the drum. The axles *d* are controlled by helical springs *g* which are attached with the one end to 45 one of the end faces of the corresponding drum and with the other end to said supports *c*, so that the drums *e* have the tendency to adopt the position in which the contact is established. The front ends of 50 the axles *d* are bent to form upwardly directed arms which are connected with one

another by a holding device *i* which is made for instance of celluloid. Instead of using a celluloid plate as holding device, a body of any other easily affected material could 55 be used, for instance of a material which melts at 60°. *k* are contact springs which bear against the drums *e* and which are fixed by means of screws *l* upon insulating plates *m* arranged upon the base plate *a*. 60 *n* are contact screws with which the ends of the leads are connected.

A protecting case *o* covers the drums *e* and the blade springs *k*, said casing having slots through which the arms *h* project. 70 Another protecting casing *p* is placed over the arms *h*; it is open at the front end and has an aperture *p'* in the rear wall which permits the access of the flames to the holding body *i*. A wire spring *q* is arranged 75 upon the front wall of the casing *o* which has bent ends designed to limit the inward movement of the arms *h*. *r* is the battery and *s* an electric alarm clock which is operated when the circuit is closed. Instead of 80 the alarm clock any other convenient acoustic device can be used, e. g. a siren, a horn or the like.

It is evident that one drum *e* would be sufficient in which case the one arm *h* would 85 be attached by the holding device *i* with a fixed support arranged at any convenient point.

When fire breaks out the holding body *i* is destroyed and releases the arms *h*, so that 90 the drums *e* can revolve under the action of the springs *g* and the insulating surfaces *f* are moved away from under the contact springs, whereby the circuit is closed.

The use of two drums as shown increases 95 the security of operation as the circuit is closed even if one of the springs *d* should be defective as the connection of the two adjacent blade springs is sufficient to close the circuit.

I claim:—

1. A thermally controlled circuit closer comprising in combination with a base plate, spring controlled contact elements pivotally mounted upon said base plate and consisting of revolvable drums, insulating surfaces upon said drums, contact springs sliding upon said drums, an arm projecting from the axle of each contact drum, and easily fusible means for holding said arms in their 105 circuit interrupting position so that at the destruction of this holding means by the 110 circuit interrupting position so that at the destruction of this holding means by the

heat developed from a fire the drums adopt automatically the circuit-closing position.

2. A thermally controlled circuit closer comprising in combination with a base plate, two parallel contact drums revolvably mounted upon said base plate, insulating surfaces upon said drums, contact springs sliding upon said drums, an arm projecting from each of the axles of said drums and an easily fusible holding means connecting said arms of the two drums in the circuit-interrupting position.

3. A thermally controlled circuit closer comprising in combination with a base plate, supports upon said base plate, two parallel drums revolvably mounted in said supports, insulating surfaces upon said drums, contact springs sliding upon said drums, an axle for each drum having an extension at one end, a head at the free end of said extension and an easily fusible holding means for connecting said heads of the two axles in the circuit-interrupting position.

4. A thermally controlled circuit closer comprising in combination with a base plate, spring controlled contact elements pivotally mounted upon said base plate and consisting of revolvable drums, insulating surfaces upon said drums consisting of pieces of fibrous material sunk into the circumferences of said drums, contact springs sliding

upon said drums, an arm projecting from the axle of each contact drum, and easily fusible means for holding said arms in their circuit-interrupting position so that at the destruction of this holding means by the heat developed from a fire the drums adopt automatically the circuit-closing position.

5. A thermally controlled circuit closer comprising in combination with a base plate, spring controlled contact elements pivotally mounted upon said base plate and consisting of revolvable drums, insulating surfaces upon said drums, contact springs sliding upon said drums, an arm projecting from the axle of each contact drum, and easily fusible means for holding said arms in their circuit interrupting position so that at the destruction of this holding means by the heat developed from a fire the drums adopt automatically the circuit-closing position, a protecting ring partly covering the contact drums and elastic abutment elements on said casing designed to limit the movement of said arms in inward direction.

In testimony whereof I affix my signature in presence of two witnesses.

PAUL ELSÄSSER.
